Inventor,
Harlow T. Stokes.

By his Attorney (H. J. Bemhard)

UNITED STATES PATENT OFFICE.

HARLOW T. STOKES, OF BROOKLYN, NEW YORK.

DESIGN FOR A CLIP FOR AUTOMOBILE BUMPERS.

Application filed February 11, 1926. Serial No. 16,491. Term of patent 14 years.

To all whom it may concern:

Be it known that I, HARLOW T. STOKES, a citizen of the United States, residing at the city of New York, borough of Brooklyn, county of Kings, State of New York, have invented a new, original, and ornamental Design for Clip for Automobile Bumpers, of which the following is a specification, reference being had to the accompanying drawing, forming part hereof.

Figure 1 is a front elevation showing the design for clip for automobile bumpers.

Figure 2 is a side or edge view showing the design for clip for automobile bumpers.

Figure 3 is a section on the line 3—3 of Figure 1.

I claim:

The ornamental design for a clip for automobile bumpers, as shown.

HARLOW T. STOKES.
